(57) **CLAIM**

The ornamental design for a stretcher transfer belt, as shown and described.

DESCRIPTION

FIG. 1 is a top perspective view of a stretcher transfer belt according to our design, showing flaps in a raised position on either side of respective support cushions and a user in ghost outline reclined on the stretcher transfer belt;
FIG. 2 is a view similar to FIG. 1, omitting said reclined user;

FIG. 3 is a top plan view of the stretcher transfer belt;
FIG. 4 is a side elevational view of the stretcher transfer belt;
FIG. 5 is an end elevational view taken from either the right or left side of FIG. 4; and,
FIG. 6 is a bottom plan view of the stretcher transfer belt.
